United States Patent Office

Des. 225,155

Patented Nov. 21, 1972

225,155

BOTTLE

Harold Schafer, Bismarck, N. Dak., assignor to Gold Seal Company, Bismarck, N. Dak.

Filed Mar. 23, 1971, Ser. No. 127,441

Term of patent 14 years

Int. Cl. D9—01

U.S. Cl. D9—143

FIG. 1 is a front elevational view of a bottle illustrating my new design;

FIG. 2 is a side elevational view thereof;

FIG. 3 is a top plan view thereof;

FIG. 4 is a bottom plan view thereof; and

FIG. 5 is a cross-sectional view taken on the line 5—5 of FIG. 1.

I claim:

The ornamental design for a bottle, as shown.
